UNITED STATES PATENT OFFICE

2,532,576

ELECTRICAL APPARATUS

Chalmers W. Sherwin, Belmont, and Henry A. Straus, Brookline, Mass., assignors, by mesne assignments, to the United States of America as represented by the Secretary of War

Application August 1, 1945, Serial No. 608,305

3 Claims. (Cl. 250—36)

1

This invention relates in general to electrical circuits and more particularly to those circuits employed in the production of sawtooth shaped electrical waves.

In many applications of electrical circuits, particularly those in which a fluorescent display is formed on the screen of a cathode ray tube, it is necessary to generate a voltage which increases linearly in amplitude for a certain period of time and then returns to a reference level, repeating this cycle of operation at a predetermined repetition rate. A wave of this type is customarily known in the art as a sawtooth wave and the designation of sawtooth as used hereafter will refer to a wave as described above.

In certain radio apparatus, such as radio object locating systems, wherein a movable antenna scans a region in space and presents on a cathode ray tube screen a visual indication of objects lying within the sector scanned, a sawtooth shaped wave which is synchronized with the motion of the scanning antenna is applied to the deflecting means of a cathode ray tube. This waveform must vary as linearly as possible and must begin and cease in a predetermined relationship to the motion of the antenna.

Accordingly, it is one object of my invention to provide a sawtooth generating circuit adaptable for use with radio object locating systems.

Another object is to provide a circuit for generating a sawtooth shaped wave of variable slope and duration.

Still another object is to provide a circuit for generating a sawtooth shaped wave having a highly linear slope.

These and further objects of the present invention will be apparent to those skilled in the art upon reference to the following specification, claims, and drawings in which:

Fig. 1 shows the connection of the various elements which comprise in combination the present invention; and,

Fig. 2 shows a cam which may be used as a means for initiating and terminating the sawtooth.

Briefly, the invention employs a so-called "boot strap" sawtooth generating circuit to produce a highly linear sawtooth wave, the slope of which is determined by voltage impressed onto the sawtooth generator from a D-C. generator which is mechanically connected to the scanning antenna. The duration of the waveform is controlled by a mechanical or electrical switch which is synchronized with rotation of the scanning antenna. The sawtooth generat-

2

ing circuit per se employed is not represented or claimed as being novel with this invention, being known in the prior art. An example of this type of circuit may be found in the application of Byron L. Havens, filed May 16, 1944, Serial No. 535,852, entitled Radio Echo System For Plotting Collision Course.

Referring now to Fig. 1, a movable antenna 5 is mechanically coupled to a driving motor 6 which in turn is coupled to a D-C. generator 7. The output voltage of generator 7 may be filtered by a suitable network 8 to remove fluctuations. The voltage is then applied to anode 10 of diode 11, cathode 12 of which is connected through resistor 13 and capacitor 14 to a point of reference, or ground, potential. Switch 29—30 is connected across capacitor 14 in such a fashion that when it is closed the capacitor is short circuited. The juncture point of resistor 13 and capacitor 14 is connected to grid 18 of vacuum tube 19, cathode 20 of which is connected through load resistor 21 to ground. Anode 23 is connected directly to a suitable source of positive voltage. Output terminal 24 is connected to cathode 20 and feedback from output terminal 24 to the high side of resistor 13 is provided by capacitor 25. Cam 27 is shown connected in the mechanical coupling path between antenna 5 and motor 6 to provide switching action of switch 29—30.

When the invention is in operation, motor 6 drives antenna 5 in its scanning pattern and in addition turns generator 7. Motor 6 may be of the variable speed type to provide any desirable scanning rate and the voltage output of generator 7 will be substantially proportional to the rate of revolution of motor 6. The output of generator 7 after being filtered is applied through the diode 11 across the series combination of resistor 13 and capacitor 14, thereby charging capacitor 14 through a relatively high resistance path. Switch 29—30, which may be mechanical as shown or alternatively an electron discharge device which is rendered conducting at intervals, is normally open. The voltage across capacitor 14, which will tend to rise exponentially at a rate determined by the voltage applied across resistor 13 and capacitor 14 and hence proportional to the rate of revolution of motor 6, is applied to grid 18 of the cathode follower stage. The exponential-voltage rise at the grid 18 is stopped by the regrounding of the capacitor 14 by the switch 29—30 near the end of the cycle then the switch reopens to repeat the cycle. This peak value of grid-

voltage rise is maintained substantially constant at any speed and, in connection with suitable choice of tube 19 and resistance 21, the cathode 20 of tube 19 is prevented from reaching saturation. Thus cathode 20 tends to follow the change in voltage appearing at grid 18, and a roughly exponential waveform appears at output terminal 24. However, by reason of the positive feedback which is employed, the actual output is considerably more linear than would be obtained from a more conventional sawtooth generator. Diode 11 prevents the changing voltages in the sawtooth generator circuit from feeding back into generator 7.

A possible method of synchronizing the production of sawtooth voltages with the motion of antenna 5 is shown in Fig. 2. Cam 27 is a disc with a notched portion therein, the extent of the notch being determined by the desired proportion of the antenna scanning cycle over which it is desired that a sawtooth voltage should be generated. In a typical instance, the notch may constitute approximately 20% of the total periphery of the disc. A spring lever 28 is rigidly attached to a fixed member at one end, the other end riding against the rim of cam 27 in such a fashion that contacts 29 and 30 are held apart except when the free end of spring 28 passes into the notched portion of cam 27. Cam 27 will normally be adjusted so that contacts 29 and 30 are opened at the beginning of a cycle of antenna scanning motion, thereby synchronizing the production of sawtooth waves with such motion.

It will be understood that possible methods of switching are not limited to a mechanical means as shown in Figs. 1 and 2 but may also be performed by electrical means. For example, an electron tube which is biased to cut off may be connected across capacitor 14. When antenna 5 moves into a predetermined position, the electron tube is fired by a photoelectric device thus causing heavy conduction through the tube which effectively short circuits capacitor 14.

From the foregoing description it will be seen that the present invention gives a highly linear sawtooth sweep voltage which is at every point synchronized with the motion of the moving antenna regardless of the rate of scan which is employed. In addition, the amplitude of the sawtooth voltage will be the same regardless of its slope, thereby obviating the need for any additional means for limiting the amount of sweep voltage applied to the cathode ray tube.

It will be apparent to those skilled in the art that changes may be made in the circuits described hereinabove without departure from the

principles of the invention. Hence, all such modifications and adaptations are claimed as may fall fairly within the spirit and scope of the hereinafter appended claims.

What is claimed is:

1. An apparatus for generating a saw-tooth voltage including a resistor and capacitor in series, said capacitor being shorted by switching means operable at a variable frequency, and a source of voltage across said resistor and capacitor varying as the frequency of switching varies for charging said capacitor through said resistor, said voltage variations being coordinated with the switching frequency of said switching means and with the charging characteristics of said resistor-capacitor combination to provide a saw-tooth voltage of substantially constant maximum amplitude across said capacitor at all switching frequencies.
2. An apparatus as in claim 1 including a multi-element tube controlled by a grid element connected to the junction of said resistor and said capacitor, a cathode element connected through a second resistor to the other side of said capacitor, a plate element connected to a source of constant voltage relative to said other side of said capacitor, a second capacitor connected between said cathode and the other end of said resistor to produce a more linear saw-tooth voltage variation, diode rectifier means between said other end of said resistor and said variable voltage source to prevent feed-back.
3. An apparatus as in claim 1 including a generator producing voltage proportional to speed as said source of voltage and an actuator for said switching means, both driven by a variable speed motor.
